[57] CLAIM

The ornamental design for a vehicle convenience console, as
shown and described.

DESCRIPTION

FIG. 1 is a left, front perspective view of a vehicle convenience console showing my new design;

FIG. 2 is a left side elevation view thereof;

FIG. 3 is a right side elevation view thereof;

FIG. 4 is a top plan view thereof; and,

FIG. 5 is a front elevation view thereof.

The vehicle convenience console has no bottom and rear
surfaces other than the side and top wall edges which lack
ornamentation.
